(57) **CLAIM**

We claim the ornamental design for a drink caddy, as shown and described.

DESCRIPTION

FIG. 1 is a front elevation view of a drink caddy showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, right side perspective view thereof;

FIG. 8 is a front elevation view thereof of the design with an unclaimed jersey; and,

FIG. 9 is a top, right side perspective view thereof.

The broken lines in the drawings showing a jersey illustrates environmental structure and forms no part of the claimed design.
